SULFONEDIIMINE COMPOUNDS

Robert G. Laughlin and Jim S. Berry, Springfield, Ohio, assignors to The Procter & Gamble Company, Cincinnati, Ohio, a corporation of Ohio
No Drawing. Filed July 13, 1966, Ser. No. 564,725
Int. Cl. C07c 147/00, 147/02
U.S. Cl. 260—551

5 Claims

This invention relates to novel sulfonediimine detergents and to detergent compositions containing these compounds.

There are several properties that are regarded as being essential for a compound to be suitable for use as a detergent. Foremost, is the cleaning ability of the compound, i.e., its ability to remove soil, e.g., from soiled clothes. In addition, the detergent should remain in active form under conditions of usage, for example, at high temperatures such as 140° F. and in aqueous solutions. Although there are a number of organic detergents which have these properties, detergent compounds such as those of the present invention which have additional desirable properties find wider scope of application.

The novel sulfonediimine compounds of this invention clean as well as tetrapropylene benzene sulfonate. They are thermally stable and resistant to hydrolysis under conditions ordinarily encountered during washing. In addition, they are compatible with anionic, nonionic, zwitterionic, ampholytic, and cationic detergents; and in combination with anionic detergents such as dodecyl benzene sulfonate have synergistic mildness properties.

The sulfonediimine compounds of this invention have the following structural formula:

wherein R is an aliphatic radical containing from about 10 to about 18 carbon atoms and R' is a methyl or ethyl radical. The aliphatic radical R can be saturated or unsaturated and branched or straight chain. Preferably, R is saturated and straight chain.

Examples of the compounds of this invention are:

methyl decyl sulfonediimine;
ethyl decyl sulfonediimine;
methyl dodecyl sulfonediimine;
methyl tetrapropylene sulfonediimine;
methyl dodecyl sulfonediimine;
ethyl dodecyl sulfonediimine;
methyl tridecyl sulfonediimine;
methyl tetradecyl sulfonediimine;
ethyl tetradecyl sulfonediimine;
ethyl pentadecyl sulfonediimine;
methyl hexadecyl sulfonediimine;
ethyl hexadecyl sulfonediimine;
methyl octadecyl sulfonediimine;
methyl oleyl sulfonediimine;
ethyl octadecyl sulfonediimine.

It is believed that symmetrical short chain sulfonediimines have been prepared in the prior art. It is surprising to find, however, that the particular unsymmetrical sulfonediimines described above have highly desirable properties for use as organic detergents.

It appears that only certain sulfonediimines have the aforementioned desired properties; in these certain sulfonediimines, R and R' must be as described above. If R is longer in chain length than 18 carbon atoms or shorter in chain length than 10 carbon atoms, desired detergency characteristics are not obtained. Likewise, if R' contains

2

more than two carbon atoms, desired detergency characteristics are not obtained.

The most preferred sulfonediimines are the C₁₂—C₁₆ methyl sulfonediimines. Particularly desirable is dodecyl methyl sulfonediimine since it exhibits a high degree of water solubility.

Sulfonediimines of this invention can be prepared by reacting a chloramine-ammonia mixture with dialkyl sulfides in an inert polar solvent at a temperature ranging from about -20° C. to about 40° C. In general, reaction times ranging from about 5 hours to about 30 hours are employed. Preferably, a reaction temperature ranging from about -5° C. to about +5° C. and reaction times ranging from about 15 hours to about 20 hours are employed. Preferably the molar ratio of chloramine to dialkyl sulfide ranges from about 3:1 to about 5:1 and is most preferably about 4:1. If molar ratios of chloramine to dialkyl sulfide of less than about 3:1 are employed herein the yield of product is too low for a practical process; molar ratios in excess of about 5:1 produce only slightly higher yields than those obtained by employing the above specified molar ratio range.

The molar ratio of ammonia to chloramine in the above chloramine-ammonia mixture can range from about 1:1 to about 20:1 or even higher. This chloramine-ammonia mixture is conveniently prepared by the Sisler technique described in Sisler, Neth and Hurley, *The Journal of the American Chemical Society*, 76, 3906 (1954).

The dialkyl sulfides for use herein have the formula RR'S wherein R and R' are defined as previously. These dialkyl sulfides are not readily available commercially. They can be conveniently prepared by reacting alkyl mercaptans such as methyl mercaptan with alpha-olefins, such as for example, 1-dodecene in the presence of a free radical initiation catalyst, such as azobisisobutyronitrile, benzoyl peroxide, tertiary-butyl perbenzoate, di-tertiary-butyl peroxide, or ultraviolet light.

The solvent for use herein must be very polar. It must dissolve the sulfide, be substantially unreactive, and promote displacement reactions. Examples of such solvents are acetonitrile, propionitrile, chloroform, methylene chloride, and lower C₁—C₄ alcohols, such as for example isopropanol.

The following equation represents a typical example of the reaction of this process:

50

Compounds of this invention are useful per se as detergent and surface active agents. Desirably they are used with other materials to form detergent compositions, as for example, liquid, bar, tablet, granular or other compositions. Such detergent compositions can contain the sulfonediimines of this invention, and water-soluble inorganic alkaline builder salts, water-soluble organic alkaline sequestrant builder salts or mixtures thereof in a ratio of sulfonediimine to builder salt of about 4:1 to about 1:20. Such detergent compositions ordinarily contain from 5% to 50% of detergent active and from 5% to 85% of builder salt.

Granular detergent compositions preferably contain about 5% to about 50% of the sulfonediimines of this invention and liquid formulations preferably contain from about 2% to about 30% of such sulfonediimines. Granular detergents preferably contain at least an equal amount of an alkaline builder salt. Liquid formulations preferably contain from about 5% to about 40% of a water-soluble alkaline builder salt, the balance of the composition being a solvent such as water, and/or other liquid vehicles. Liq-

uid formulations can also contain a hydrotroping electrolyte, e.g., sodium toluene sulfonate. All percentages and parts herein are by weight unless specified otherwise.

Water-soluble inorganic alkaline builder salts which can be used in this invention alone or in admixture are alkali metal carbonates, borates, phosphates, polyphosphates, bicarbonates and silicates. Ammonium or substituted ammonium, e.g., triethanol ammonium, salts of these materials can also be used. Specific examples of suitable salts are sodium tripolyphosphate, sodium carbonate, sodium tetraborate, sodium and potassium pyrophosphate, sodium and ammonium bicarbonate, potassium tripolyphosphate, sodium hexaphosphate, sodium sesquicarbonate, sodium orthophosphate and potassium bicarbonate. The preferred inorganic alkaline builders according to this invention are alkali metal tripolyphosphates for built granular and tablet compositions and alkali metal pyrophosphates for built liquid compositions. Potassium is the preferred alkali metal used in liquid compositions and sodium finds best application for granular or tablet compositions.

Examples of suitable organic alkaline sequestrant builder salts used in this invention alone or in admixture are alkali metal, ammonium or substituted ammonium, aminocarboxylates, e.g., sodium and potassium ethylenediaminetetraacetate, sodium and potassium N-(2-hydroxyethyl)-ethylenediaminetriacetates, sodium and potassium nitrilotriacetates and sodium, potassium and triethanolammonium N-(2-hydroxyethyl)-nitrilotriacetates. Mixed salts of these polycarboxylates are also suitable. The alkali metal salts of phytic acid, e.g., sodium phytate are also suitable as organic alkaline sequestrant builder salts (see U.S. Patent 2,739,942). Also suitable as organic alkaline sequestrant builder salts are the water-soluble salts of polycarboxylate polymers and copolymers as described in the copending application of Francis L. Diehl, Ser. No. 269,359, filed Apr. 1, 1963 (e.g., polymers of itaconic acid, aconitic acid, maleic acid, mesaconic acid, fumaric acid, methylene malonic acid, and citric acid and copolymers with themselves and other compatible monomers such as ethylene).

Polyphosphonates are also valuable builders in terms of the present invention, including specifically sodium and potassium salts of ethane-1-hydroxy-1,1-diphosphonate, sodium and potassium salts of methylene diphosphonate, sodium and potassium salts of ethylene diphosphonate, and sodium and potassium salts of ethane-1,1,2-triphosphonate. Other examples include the alkali metal salts of ethane-2-carboxy-1,1-diphosphonic acid, hydroxymethanediphosphonic acid, carboxyldiphosphonic acid, ethane-1-hydroxy-1,1,2-triphosphonic acid, ethane-2-hydroxy-1,1,2-triphosphonic acid, propane-1,1,3,3-tetraphosphonic acid, propane-1,1,2,3-tetraphosphonic acid and propane-1,2,2,3-tetraphosphonic acid.

Besides the builders being used together with sulfonediimines, it is also possible according to the present invention to use the sulfonediimine compounds of this invention in combination with other cleaning agents such as anionic, ampholytic, zwitterionic, and other nonionic organic detergent surfactant compounds. When it is desired to use such sulfonediimine compounds in combination with other detergent compounds, they are preferably utilized with anionic detergents because of the sudsing characteristics of the latter. The ratio of the sulfonediimine to such other detergent compound is from about 10:1 to 1:5. If it is desired to use such a sulfonediimine in admixture with another detergent compound as the active portion of a cleaning composition, the ratio of such a mixture to the builder salt should be within the previously prescribed range of 4:1 to 1:20. A composition prepared along these lines can contain from 5% to 50% of such a mixture and 5% to 85% of a builder salt selected from water-soluble inorganic alkaline builder salts, water-soluble organic sequestrant builder salts, and mixtures thereof, within the prescribed ratio range.

Examples of anionic soap detergents which can be used

in admixture with the sulfonediimine, if desired, are the sodium, potassium, ammonium and alkylolammonium salts of higher detergent range fatty acids (C₁₀-C₂₀). Particularly useful are the sodium and potassium salts of the mixtures of fatty acids derived from coconut oil and tallow, i.e., sodium or potassium tallow and coconut soap. Examples of suitable anionic organic non-soap detergents in the form of their water-soluble salts are: alkylglyceryl-ethersulfonates; alkyl sulfates; alkyl monoglyceride sulfates or sulfonates; alkylpolyethoxy ether sulfates; acyl-sarcosinates; acyl esters of isethionates; N-acyl-N-methyltaurides, alkylbenzenesulfonates wherein the alkyl substituent is straight chain or branched chain, sulfonated alpha-olefins; alkylphenol polyethoxy sulfonates. In these compounds the alkyl and acyl groups, respectively, contain 10 to 20 carbon atoms. They are used in the form of water-soluble salts, the sodium, potassium, ammonium, and alkylolammonium salts, for example. Specific examples are: sodium lauryl sulfate, sodium tallow alkyl sulfate; sodium salt of sulfonated alpha-tridecene; potassium N-methyl-N-lauroyl tauride; triethanolammonium tetrapropylbenzene sulfonate; sodium (linear) dodecyl benzene sulfonate.

Examples of other nonionic organic detergents which can be used in the compositions of this invention, if desired, are: polyethylene oxide condensates of alkylphenols where in the alkyl group contains from 8 to 15 carbon atoms (e.g., t-octylphenol) and the ethylene oxide is present in a molar ratio of ethylene oxide to alkylphenol in the range of 8:1 to 20:1; condensation products of ethylene oxide with the product resulting from the reaction of propylene oxide and ethylene diamine wherein the molecular weight of the condensation products ranges from 5000 to 11,000; the condensation products of from about 5 to 30 moles of ethylene oxide with one mole of a straight or branched chain aliphatic alcohol containing from 8 to 18 carbon atoms, e.g., condensation product of 6 moles of ethylene oxide with one mole of lauryl alcohol; higher alkyl di-lower alkyl amine or phosphine oxides, e.g., dodecyldimethylamine oxide or dodecyldimethyl phosphine oxide; alkyl methyl sulfoxides such as dodecyl methyl sulfoxide.

Ampholytic synthetic detergents can be broadly described as derivatives of aliphatic secondary and tertiary amines in which the aliphatic radical can be straight chain or branched and wherein one of the aliphatic substituents contains from about 8 to about 18 carbon atoms and one contains an anionic water solubilizing group, e.g., carboxy, sulfonate, sulfate, phosphate, or phosphonate. Examples of compounds falling within this definition are sodium 3-dodecylaminopropionate, sodium 3-(N-methyl-N-hexadecylamine) 2-hydroxy propane-1-sulfonate and its dodecyl homolog, sodium 3-dodecylaminopropane sulfonate, sodium dodecyl-beta-alanine, sodium N-alkyltaurines such as the one prepared by reacting dodecylamine with sodium isethionate according to the teaching of United States Letters Patent Number 2,658,072, N-higher alkyl aspartic acids such as those produced according to the teaching of United States Letters Patent Number 2,438,091, and the products sold under the trade name "Miranol" and described in United States Letters Patent Number 2,528,378.

Zwitterionic synthetic detergents can be broadly described as derivatives of aliphatic quaternary ammonium, phosphonium, and sulfonium compounds, in which the aliphatic radical may be straight chain or branched, and wherein one of the aliphatic substituents contains from about 10 to about 18 carbon atoms and one contains an anionic water solubilization group, e.g., carboxy, sulfo, or sulfato. Examples of compounds falling within this definition are: 3-(N,N-dimethyl-N-hexadecylammonio)-2-hydroxypropane-1-sulfonate and the corresponding dodecyl and tetradecyl homologs and 3-(N,N-dimethyl-N-dodecylammonio)-propane-1-sulfonate and the corresponding hexadecyl and tetradecyl homologs.

The detergent compositions of this invention can also contain any of the usual adjuvants, diluents and additives, for example, perfumes, anti-tarnishing agents, anti-redeposition agents, bacteriostatic agents, dyes, fluorescers, suds builders, suds depressors and the like, without detracting from the advantageous properties of the composition.

Certain mixtures of the sulfonediimines of this invention and alkylbenzene sulfonates exhibit superior and unexpected mildness characteristics. In certain ranges, and under comparable conditions of exposure, mixtures of these two detergent compounds in aqueous solution are milder to the skin than either one alone. Thickening, dryness and cracking of the skin of test animals under exaggerated exposures to solutions of such mixtures are markedly reduced and in some cases disappear in comparison to similar exposures to solutions of either of the actives alone. This mildness effect is very advantageous since combinations of the alkyl benzene sulfonates and sulfonediimines in compositions of the present invention are efficient detergents. The cleansing compositions of this invention having superior mildness characteristics comprise mixtures of alkylbenzenesulfonates having alkyl radicals ranging from about 9 to about 15 carbon atoms and the sulfonediimines of this invention, the ratio of the respective ingredients being in the range of about 5:1 to about 1:10.

The alkylbenzenesulfonates in compositions of this invention are the water-soluble salts, such as the alkali metal (e.g., sodium and potassium), ammonium and substituted ammonium (e.g., triethanolamine) salts, of sulfonated alkylbenzene in which the alkyl radicals range from about 9 to about 15 carbon atoms. Especially preferred for use herein are the linear alkylbenzenesulfonates, for example, linear dodecylbenzene sulfonate. Also useful herein are alkylbenzenesulfonates having their alkyl chain derived from propylene, for example tetrapropylenebenzenesulfonate. These alkylbenzenesulfonates are commonly used as a sodium salt.

In the testing of detergent compounds and compositions for mildness and for the unexpected mildness effect, skin is contacted by immersion or other means with a solution of the detergent under standardized conditions as more fully described below. A 1 to 10 scale is used to rate the effects of prolonged exposure on the skin. Grade 10 represents ideal or perfect skin (soft, smooth and flexible) and the effect of a theoretically perfectly mild detergent; Grade 1 represents severely irritated skin. Other values represent gradations of severity between these extremes. Grade 1 in a guinea pig immersion test indicates severely thickened, dry, cracked and bleeding skin, i.e., extreme irritation. Grade 1 in exaggerated tests on human subjects indicates severe redness and dryness of the skin. Thus, the exaggerated exposure tests on animals are much more extreme than those conducted on human subjects.

There is a good correlation between the results of exaggerated exposure tests on animals and the results of normal use tests on humans; the former can be relied on to grade the relative mildness of detergents toward the human skin.

As used in the examples, the graded guinea pig immersion tests consist of immersing the animal up to the thorax in the test solutions at 37° C. for a 4½ hour period per day for 3 consecutive days. The animals are graded 3 days after the last immersion. The grades given in the examples are the average of the results on not less than three animals. It will be understood by those with experience in biological experiments that there is variation in the reactions of individuals, within a group, to expose the chemical solutions; this is true whether the individuals are guinea pigs or humans.

The following examples are illustrative of the present invention and are not to be construed in any way as limiting its scope.

EXAMPLE I

Preparation of methyl dodecyl sulfonediimine

In a two-liter three-neck flask equipped with a 10 mm. diameter gas inlet tube, mechanical stirrer, and drying tube, 10 were placed 86.4 grams (0.400 mole) methyl dodecyl sulfide and 1300 ml. dry acetonitrile. A chloramine-ammonia mixture generated according to the previously described Sisler technique was passed into the flask at 0-5° C. during 15 four one-hour periods. The chloramine was passed into the flask at the rate of 0.4 mole per hour or 1.6 moles over the entire four-hour period. Ammonia in admixture with the chloramine was passed into the flask at the rate of 4.25 moles per hour; the mole ratio of ammonia to chloramine in the mixture was about 10.6:1. 20 After each one-hour gas addition period the ammonium chloride which precipitated in the chloramine generator was removed from the system. The reaction was then stirred for 15 hours at 0° C. and filtered cold.

The filter cake was extracted thoroughly with isopropanol and the bulk of the isopropanol was removed in 25 vacuo using a rotary evaporator. The residue was then redissolved in isopropanol and washed three times with 50% aqueous potassium carbonate. The isopropanol was again evaporated and the solid residue recrystallized from 30 ethyl acetate to provide 46 grams of substantially pure methyl dodecyl sulfonediimine.

A similar preparation was carried out exactly as above except that 1300 ml. of isopropanol was substituted for the 1300 ml. dry acetonitrile employed as a reaction solvent above. After purification this preparation yielded 44 grams of methyl dodecyl sulfonediimine.

Methyl decyl sulfonediimine was prepared from 0.3 mole methyldecyl sulfide and 1.2 mole chloramine in admixture with about 12.8 moles ammonia in acetonitrile 40 following the same procedure described above for the dodecyl homolog. The resulting reaction mixture was purified to yield 29.5 grams of methyl decyl sulfonediimine.

Methyl tetradecyl sulfonediimine, methyl hexadecyl sulfonediimine and ethyl octadecyl sulfonediimine can be 45 prepared by employing the above procedure with the corresponding dialkyl sulfide in isopropanol solvent.

The cleaning ability of the above-synthesized compounds in the washing of clothes was comparable to that of tetrapropylene alkylbenzenesulfonate.

50 The following aqueous solutions (distilled water) were compared in graded guinea pig immersion tests:

Test solution:	Grade
Sodium dodecylbenzenesulfonate (tetrapropylene) (0.2%)	3
Methyl dodecyl sulfonediimine (0.2%)	2
Sodium dodecylbenzenesulfonate (tetrapropylene) (0.2%) + methyl dodecyl sulfonediimine (0.2%)	9

Similar results are achieved when linear dodecylbenzene sulfonate or other of the above-mentioned alkylbenzenesulfonates are substituted for the above tetrapropylene dodecylbenzenesulfonate and/or other sulfonediimines of this invention, for example, methyl decyl sulfonediimine, methyl tetradecyl sulfonediimine, methyl hexadecyl sulfonediimine or ethyl octadecyl sulfonediimine 60 are substituted for the methyl dodecyl sulfonediimine above.

A significant unexpected mildness effect is apparent in the 70 solution of a mixture of alkylbenzenesulfonate and the sulfonediimines of this invention in a 1:1 ratio as compared to solutions of the individual detergents alone.

The following examples illustrate detergent compositions containing the sulfonediimines of this invention which can be used under conditions of ordinary usage to 75 clean, for example, soiled clothing or soiled dishes.

EXAMPLE II

Solid—Granules

	Percent
Methyl dodecyl sulfonediimine	17.5
Sodium tripolyphosphate	50.0
Sodium silicate ($\text{Na}_2\text{O}:\text{SiO}_2=1:2.5$)	10.0
Sodium sulfate	17.5
Moisture	5.0

EXAMPLE III

Compressed granules—Tablet

	Percent
Methyl hexadecyl sulfonediimine	31.0
Tetrasodium pyrophosphate	52.0
Trisodium phosphate	10.0
Moisture	7.0

EXAMPLE IV

Solid—Granules

	Percent
Ethyl octadecyl sulfonediimine	32.2
Trisodium ethane-1-hydroxy-1,1,2-triphosphonate	64.0
Moisture	4.0

EXAMPLE V

Solid—Granules

	Percent
Methyl dodecyl sulfonediimine	10.0
Sodium (linear) dodecylbenzenesulfonate	10.0
Sodium tripolyphosphate	50.0
Sodium sulfate	30.0

EXAMPLE VI

Solid—Granules

	Percent
Methyl tetradecyl sulfonediimine	10.0
Sodium (tetrapropylene) dodecylbenzenesulfonate	10.0
Sodium tripolyphosphate	50.0
Sodium sulfate	30.0

EXAMPLE VII

Solid—Granules

	Percent
3-(<i>N,N</i> -dimethyl- <i>N</i> -hexadecylammonio) - propane-1-sulfonate	20.0
Methyl hexadecyl sulfonediimine	25.0
Sodium tripolyphosphate	35.0
Sodium carbonate	10.0
Sodium silicate ($\text{Na}_2\text{O}:\text{SiO}_2=1:2.5$)	5.0
Moisture	5.0

EXAMPLE VIII

Solid—Granules

	Percent
Methyl dodecyl sulfonediimine	20.0
Sodium tallow alcohol sulfate	10.0
Trisodium ethane-1-hydroxy-1,1-diphosphonate	20.0
Sodium tripolyphosphate	10.0
Sodium nitrilotriacetate	10.0
Sodium sulfate	8.0
Sodium silicate ($\text{Na}_2\text{O}:\text{SiO}_2=1:2.5$)	11.0
Moisture	11.0

EXAMPLE IX

Liquid

	Percent
Methyl decyl sulfonediimine	5.0
Sodium salt of SO_3 sulfonated 1:1 weight mixture of dodecene and alpha-tetradecene	10.0
Tetrapotassium pyrophosphate	19.0
Sodium silicate ($\text{Na}_2\text{O}:\text{SiO}_2=1:1.6$)	3.8
Potassium toluene sulfonate	8.5
Carboxymethyl hydroxyethyl cellulose	.3
Water	Balance

EXAMPLE X

Liquid

	Percent
Methyl dodecyl sulfonediimine	6.0
Sodium (linear) dodecylbenzenesulfonate	6.0
Tetrapotassium propane-1,1,3,3-tetraphosphonate	20.0
Sodium silicate ($\text{Na}_2\text{O}:\text{SiO}_2=1:1.6$)	3.8
Potassium toluene sulfonate	8.5
Carboxymethyl hydroxyethyl cellulose	.3
Water	Balance

EXAMPLE XI

Solid—Granules

	Percent
Ethyl hexadecyl sulfonediimine	5.0
Condensation product of 10 moles of ethylene oxide and one mole of tallow fatty alcohol	5.0
Sodium (linear) tridecyl benzenesulfonate	10.0
Dodecyldimethyl phosphine oxide	5.0
Coconut oil soap	5.0
Sodium tripolyphosphate	50.0
Tetrasodium ethylene diamine tetraacetate	20.0

Good detergency effects are also obtained when in the above examples the following builders are substituted for those employed in such examples: tripolyphosphates; pyrophosphates; ethylene diaminetetraacetates; *N*-(2-hydroxyethyl)-ethylenediamine triacetates; nitrile triacetates; *N*-(2-hydroxyethyl)-nitrilodiacetates; phytates; polycarboxylate polymers; and polyphosphonates.

It will be appreciated that the sulfonediimine compounds used in the present invention can be incorporated into many other liquid or granular detergent compositions with suitable adjustments being made in the other components.

Materials which are considered normal and desirable additives in liquid or granule detergent compositions can be added to the compositions of this invention without adversely affecting or modifying basic cleaning characteristics. For example, a tarnish inhibitor such as benzotriazole or ethylene thiourea may be added in amounts up to about 1%.

What is claimed is:

1. A sulfonediimine having the structural formula

wherein R is an aliphatic radical containing from about 10 to about 18 carbon atoms and R' is selected from the group consisting of methyl and ethyl radicals.

2. Methyl decyl sulfonediimine.

3. Methyl dodecyl sulfonediimine.

4. Methyl tetradecyl sulfonediimine.

5. Methyl hexadecyl sulfonediimine.
